CHILD'S FLEXION WHEELCHAIR

Thomas R. Blue, 17802 Norwood Park,
Tustin, Calif. 92680

Filed Sept. 2, 1975, Ser. No. 609,311

Term of patent 14 years

Int. Cl. D12—12

U.S. Cl. D12—131

FIGURE 1

FIGURE 2

FIGURE 3

FIG. 1 is a front perspective view of a child's flexion wheelchair showing my new design;

FIG. 2 is a rear perspective view thereof; and

FIG. 3 is a bottom perspective view thereof, with the footrest portion pivoted to a different position from that shown in FIGS. 1 and 2 for clarity of illustration.

I claim:

The ornamental design for a child's flexion wheelchair, as shown.
